UNITED STATES PATENT OFFICE.

HERMANN SUIDA, OF MODLING, AUSTRIA, ASSIGNOR TO I. G. FARBEINDUSTRIE AKTIENGESELLSCHAFT, OF FRANKFORT-ON-THE-MAIN, GERMANY, A CORPORATION OF GERMANY.

PROCESS FOR OBTAINING GASES RICH IN ETHYLENE.

No Drawing. Application filed June 24, 1924, Serial No. 722,132, and in Austria June 26, 1923.

It is known that by destructive distillation of tar oils and of certain fractions of mineral oils gases containing olefines may be obtained. This process has been used for a long time and on a large scale for the manufacture of oil gas. As a rule these gases, however, contain not more than 20% of olefines. Furthermore the olefines only partly consist of ethylene and besides contain considerable quantities of higher olefines whereby the value of the gases is substantially impaired for some purposes since the component of high commercial value is ethylene. The statements given in the textbooks and other publications of the art are not correct as the olefines are in most cases not specified but indicated as an entirety, the total mixture being sometimes designated as "ethylene" no separation of the olefines by analysis having occurred. Upon examination it may, however, be shown that the temperatures which yield a high percentage of mixed olefines (600-700° C.) are those, at which the higher homologues prevail. At higher temperatures the production of olefines is reduced in favor of methane and hydrogen, though the main constituent of the olefine mixture is then ethylene.

I have made the surprising discovery, that it is possible to obtain at high temperatures gases rich in olefines and particularly in ethylene if care be taken to avoid a destruction of the ethylene once formed. This advantage may be attained by introducing steam together with the oil, more particularly saturated or superheated steam, and by working at temperatures of 800 to 900° C. Under these conditions tar oils of different origin (brown coal generator tar oil, tar oil resulting by smouldering brown coal, black coal tar oil, produced at low temperature at which destruction will not occur, or fractions of said oils) will yield gases with 40 to 50% of olefines nearly exclusively consisting of ethylene. It is a surprising fact that by the use of steam at 800 to 900° C. not only the formation of ethylene is improved but also the output of olefines calculated on the quantity of tar oil used as starting material is considerably raised. Under equal conditions but in absence of steam, gases of a much lower content of olefines are obtained. The destructive distilla-

tion of tar oils, mineral oils and resinous oils in the presence of steam, has been described in British Patent No. 19,096/1895 and in German Patent No. 36,134 A. D. 1886. The processes described in these patents were, however, carried out to serve other purposes, namely to obtain oils of low boiling point and as to the manufacture of heating gases, no particulars as regards the temperature were disclosed in said patents.

The above described behavior of the tar oils at the indicated temperatures could not be foreseen since olefines practically can not be obtained at such high temperatures and it was not likely that the presence of water vapor would thus modify the cracking process apart from lowering the temperature of distillation which however, does not occur in this case. As regards the improvement of the output of olefines a process by which water-gas is simultaneously produced owing to the presence of steam and carbon produced by destruction is out of the question, since by such process only hydrogen and carbonmonoxide but no olefines could be produced and by combination of the hydrogen with the olefines their output could only be reduced and not raised.

Example.

When oil, for instance such oil as will be obtained by simple distillation of brown coal generator tar and having a boiling point of 300 to 350° C. are introduced in a crude state into an iron tube of 900° C. with an equal quantity of steam, considerable quantities by weight of a gas containing 44 to 48% ethylene will be obtained besides liquid distillates. The total gas output amounts to about 300 to 400 liters for each kilogram of oil. On using more or less steam the output will be reduced. It is therefore most advantageous to use equal quantities of oil and steam. If the distillation be carried out in the absence of steam but with otherwise similar conditions a gas with 30% of olefines is obtained.

Instead of brown coal tar oils, I may use as well black coal tar oil obtained by distillation at low temperatures or fractions of said oil, which are more advantageous than the ordinary mineral oil fractions in that the gases do not contain heavy saturated

hydrocarbons besides the olefines, whereas fractions of mineral oils, such as gas oil upon cracking will always yield large quantities of ethane which cannot be separated 5 from the ethylene without difficulty.

The gases obtained by the process according to my invention may easily be worked down to concentrated ethylene gas in a known manner for instance by concentrating 10 the ethylene by means of active charcoal; by a single passage of the gas over charcoal a 80 to 90% ethylene may be obtained. This is impossible with gases obtained by cracking mineral oils which are rich in 15 olefines but in which the concentration of ethylene is hindered by the presence of ethane.

It is to be understood that the concentration of the crude gas may as well be carried out by partial liquefaction and distillation.

What I claim is:

1. A process for obtaining gases rich in ethylene which consists in subjecting tar 20 oils of a high boiling point to destructive 25

distillation in the presence of steam and at temperatures of 800 to 900° C.

2. A process for obtaining gases rich in ethylene which consists in subjecting lignite tar oils of a high boiling point to destructive distillation in the presence of steam and at temperatures of 800 to 900° C. 30

3. A process for obtaining gases rich in ethylene which consists in subjecting tar oils of a high boiling point to destructive distillation in the presence of steam and at temperatures of 800 to 900° C., the quantity by weight of steam being approximately 35 the same as that of the tar oil.

4. A process for obtaining gases rich in ethylene which consists in subjecting lignite tar oils of a high boiling point to destructive distillation in the presence of steam and at temperatures of 800 to 900° C., the quantity by weight of steam being approximately 40 the same as that of the tar oil. 45

In testimony whereof I have hereunto set my hand.

HERMANN SUIDA.

CERTIFICATE OF CORRECTION.

Patent No. 1,726,048.

Granted August 27, 1929, to

HERMANN SUIDA.

It is hereby certified that error appears in the printed specification of the above numbered patent requiring correction as follows: Page 1, line 84, for the word "oil" both occurrences, read "oils"; and that the said Letters Patent should be read with this correction therein that the same may conform to the record of the case in the Patent Office.

Signed and sealed this 1st day of October, A. D. 1929.
